UNITED STATES PATENT OFFICE.

GRIGORY KOVALEVICH, OF SOUTH PORTLAND, OREGON.

PROPELLER.

1,105,801.

Specification of Letters Patent. Patented Aug. 4, 1914.

Application filed January 22, 1914. Serial No. 813,743.

To all whom it may concern:

Be it known that I, GRIGORY KOVALEVICH, a subject of the Emperor of Russia, residing at South Portland, in the county of Multnomah, State of Oregon, have invented certain new and useful Improvements in Propellers, of which the following is a description, reference being had to the accompanying drawings, forming a part thereof.

10 My invention relates to screw propellers and has for its objects to provide a propeller which will be simple and inexpensive in construction and at the same time be 15 highly efficient and free from the difficulties which are experienced in propeller wheels as usually constructed.

With these and other objects hereinafter explained my invention consists in the construction and combination of elements hereinafter described and particularly pointed out in the claims.

20 Referring to the drawings Figure 1 is an elevation of the front end of the propeller embodying my invention. Fig. 2 is a front elevation of one of the blades of the propeller shown in Fig. 1 with its connections to the shaft. Fig. 3 is a side view of the 25 blade and connections shown in Fig. 2 taken from the rear of Fig. 2 and Fig. 4 is a detail view showing the connection of the stays to the shaft.

30 In the drawings 1 indicates a central shaft here shown as hollow but which may be of any desired construction.

25 2 indicates a blade extending from front to rear of the propeller and extending inward from the outer periphery a distance which in the propeller shown is substantially 35 half the distance from the periphery of the propeller to the periphery of the shaft and somewhat more than one third of the radius of the propeller, though this dimension of the blade may be varied as desired. In the propeller shown six of these blades are shown 40 spaced equally about the circumference but a less or greater number may be used, and in the propeller shown the outer edges of the blades may rest against and be secured to a 45 rim which may or may not be used. The blades are, of course, arranged at an angle to the axis of the propeller as is usual in screw propellers. The leading edges 4 of the 50 blades are so arranged that they will each lie in the plane of a radius as shown when 55 viewed from the front as shown in Fig. 1

and they are also so cut off that the lines of their edges when viewed from the side will lie in the plane of a radius.

Each of the blades is secured in position 60 by stays here shown as four in number three of which, indicated by 5, 6 and 8 are secured at their outer ends to the rear face of the blade and the other, indicated by 7, is secured to the trailing edge of the front or 65 cutting face of the blade. The stays are all secured at their inner ends to the shaft 1 as hereinafter described. The stay 5 is secured at its outer end by rivet 9 or other convenient means to the blade 2 near its 70 leading edge and near its outer edge. The stay is formed of a flat strip and its outer portion 10, is arranged to lie against the rear face of the blade. The portion 11 of this stay between the inner edge of the 75 blade and the shaft 1 is so twisted that the inner end of the stay is in line with the axis of the shaft. The inner end of this stay is upset or bent to form an inwardly extending lug 12 which fits in a recess 13 formed 80 in the periphery of the shaft 1, this recess 13 being so formed that the outer edge of the stay at its inner end will be flush with the peripheral surface of the shaft. A bolt or screw 14 near the inner end of the stay 85 holds it to the shaft, the head of this bolt or screw being countersunk into the outer surface of the stay so as to present no obstruction. The stay 7 is secured to the front face of the blade near its trailing edge by a 90 rivet or other fastening device 15. The outer portion 16 of this stay is arranged to lie against the face of the blade and the shaft and is so twisted that its inner end will be in line with the axis. This stay is 95 provided at its inner end with a lug 12', as above described in connection with stay 5 and is secured in a recess 13' as also above described in connection with stay 5. The recesses 13 and 13' in which the ends of stay 100 5 and 8, are so arranged that they are diametrically opposite on the periphery of the shaft 1. But while the stay 5 is arranged as shown in Fig. 3 so as to extend inward at right angles to the axis of the shaft, the 105 stay 7 extends inward and rearward at an oblique angle to the axis of the shaft as shown in Fig. 3 and the recess 13' in which its end is formed at an oblique angle to the axis.

Stay 6 is secured at its outer end to the rear face of the blade near its trailing edge

by a rivet or other fastening device 18 this fastening device preferably, as shown, passing through the stay 5. The outer portion 19 of this stay lies in a plane parallel with 5 the rear face of the blade and its portion 20 between the inner edge of the blade and the shaft is so twisted that its inner end is in line with the axis. This stay instead of extending inward at right angles to the axis 10 of the shaft extends inward and forward at an angle oblique to the axis and the recess 13² in which its end 12 is secured is also arranged at an angle oblique to the axis.

Stay 8 is secured at its outer end to the 15 rear face of the blade near its rear end by rivet or other fastening device 21. The outer portion 22 of this stay lies against the rear face of the blade, and the portion 23 between the inner edge of the blade and the 20 shaft is so twisted that its inner end is in line with the axis. Its inner end is provided with a lug 12 which rests in and is secured in recess 13³ as above described in connection with stay 5. This stay extends inward 25 at right angles to the axis of the shaft as does stay 5. The rivet or other fastening device which secures the outer end of stay 8 to the blade preferably passes through the outer portion 22 of stay 8.

30 It will be seen from the above description that stays 5 and 6 being united at the outer end of stay 6 and having their inner ends widely separated on the periphery of the shaft as shown on Fig. 2 form a brace to resist 35 rotary movement of the blade relative to the shaft, and from the fact that their inner ends are widely separated in the direction of the axis of the shaft as shown in Fig. 3, they also serve as a brace against any 40 rearward longitudinal movement of the blade, the stays 7 and 8 being similarly arranged as shown in Figs. 2 and 3 serve to brace the blade against rotary movement and also against any forward longitudinal 45 movement. The stays 6 and 7 extending as shown in Fig. 3 in opposite directions and being connected at their outer ends by the blade serve as the outer members of a truss the supporting members of which are the 50 stays 5 and 8, as shown in Fig. 3.

The blade 2 is preferably formed of sheet or plate metal and by the construction shown is firmly and rigidly held in position by the stays whether the rim 3 is used or not.

55 By reason of the fact that stays 5, 6 and

8 are all secured to the rear face of the blade, the front or cutting face of the blade presents a smooth unbroken surface to the water for nearly its whole extent, the only break in its surface being the upper end of stay 7 which is near the rear end of the blade.

The twistings of the portions of the stays 5, 6 and 7 and 8 as above described between the inner edge of the blade and the shaft 65 causes them to present comparatively thin edges to the water in the center portion of the wheel and thus avoids churning of this water and permits the water to pass through with the least possible obstruction. By securing the inner ends of the stays as described the peripheral surface of the shaft is made as nearly unbroken and smooth as possible.

Of course when the propeller is operated 75 in reverse direction the rear faces of the blades will become, as regards action on the water, front faces and as these faces are broken by the outer ends of stays 5, 6 and 8 the propeller will not be as efficient as when 80 rotated in the other direction but will still be highly efficient.

Having thus described my invention what I claim is:

1. A propeller, having a central shaft and 85 blades extending inward from the periphery a distance less than the length of a radius and stays connected at their outer ends to a blade and at their inner ends to the shaft, the stays being arranged in pairs, the stays 90 of each pair being secured together near their outer ends and having their inner ends secured to the shaft at points widely separated on its periphery.

2. A propeller having a central shaft and 95 blades extending inward from the periphery a distance less than the length of a radius and stays connected at their outer ends to a blade and at their inner ends to the shaft, the stays being arranged in pairs, the stays 100 of each pair being secured together near their outer ends and having their inner ends secured to the shaft at points widely separated on its periphery and also widely separated longitudinally of its axis. 105

This specification signed and witnessed this 22nd day of January, A. D. 1914.

GRIGORY KOVALEVICH.

In the presence of—

JACOB M. SASLAN.

JOE OMBER.
